CARBURETOR

Harry L. Johnson, Waukegan, Ill., assignor to
 Johnson Brothers Engineering Corporation,
 Waukegan, Ill., a corporation of Indiana

Application June 11, 1934, Serial No. 729,950

5 Claims. (Cl. 261—41)

This invention relates in general to a carburetor and has more particular reference to a delay feed carburetor having a jet nozzle for supplying fuel at low or medium speeds and an open throttle 5 nozzle for providing a delay feed.

In the ordinary operation of a two-cycle or other gasoline engine, a quantity of fuel condenses and collects in the pipes and passages from the ordinary carburetor to the combustion 10 chamber of the engine so that when the throttle is opened to its fullest or nearly full extent, an immediate additional supply of fuel is neither desirable nor necessary until the fuel which has collected in the passages from the carburetor to 15 the combustion chamber has been absorbed or carried away. The present invention therefore provides a delay interval for the additional open throttle fuel feed which is sufficient to take care of the condensation and accumulation of fuel before 20 the additional feed is effective.

It is therefore an important object of the present invention to provide a carburetor with a fuel jet nozzle for ordinary and slow speed running and an additional fuel jet nozzle with a supply 25 pipe having a certain capacity and providing a delay feed for the additional jet nozzle which is operative only at high speed or with an approximately full open throttle.

A further object of the invention is in the provision of a fuel feeding device which provides a rapid acceleration of an engine from low throttle speeds to medium and full open throttle speeds and to cause a smooth feeding and supply of fuel to an engine by the construction herein shown 30 and described.

Other objects of the invention will appear hereinafter, the preferred construction being illustrated in the accompanying drawings, in which

Fig. 1 is a side elevation of a delay feed carburetor in accordance with the principles of this invention;

Fig. 2 is a section taken on the line 2—2 of Fig. 1;

Fig. 3 is a section taken on the line 3—3 of Fig. 45 1; and

Fig. 4 is a part sectional view taken on the line 4—4 of Fig. 1.

When an engine is running normally at low or medium speed, and particularly an engine of the 50 two-cycle type in which oil is frequently mixed with the gasoline for lubricating the engine, it is found that the lubricant as well as the fuel tends to condense upon the walls of the fuel passage from the carburetor to the engine, the amount of 55 such condensation or collection depending more

or less upon the efficiency of the carburetor as a fuel mixing device. When the throttle is opened to a greater extent, the additional flow of air will take up the condensation or collection of oil or fuel in the passages from the carburetor and will cause acceleration of the engine without the immediate addition of more fuel. If additional fuel is supplied immediately under such conditions there will be an excess of fuel and the smooth acceleration of the engine will be retarded rather than assisted. The present invention provides for a retarded supply of additional fuel due to the capacity of the pipe itself and the time interval necessary to fill the pipe and discharge fuel from the high speed jet nozzle.

Referring now more particularly to the drawings, a carburetor block or body 6 has an air inlet 7, a throttle chamber 8 and a fuel passage 9 formed therein. At one side of the block is an extension forming a fuel chamber 10 having a 20 threaded tubular portion 11 at the bottom connected by means of a pipe 12 with a suitable source of fuel supply. In the tubular portion 11 is a perforated valve plug 13 through which extends a valve stem 14 carrying a valve 15 to close 25 the valve opening 16. Mounted on the stem 14 in the chamber 10 is a float 17 carrying a float adjustment plate 18 secured to the float by a screw 19. The upper end of the stem extends through a centering opening in a cap 20 which 30 closes the top of the chamber 10, the cap being held yieldingly in place by a spring 21 extending laterally from the side of the chamber.

In the throttle chamber 8 which is preferably circular in transverse section is a bottom filler 35 plate 22 (Figs. 2 and 3) held in place by a screw 23 inserted through the wall of the body 6. The inner face of this plate forms a chord at the bottom of the chamber 8 and extending upwardly through a passage 24 in the bottom 6 is a lower 40 jet nozzle 25 having an opening or openings 26 at its upper end closely adjacent the lower edge of the throttle chamber and the lower side of the plate 22. Rotatable in the chamber 8 is a throttle 27 which arches the chamber 8 from the 45 opposite central portions thereof as shown in Fig. 3, but is segmental in cross section as shown in Fig. 2, to substantially close the passage when rotated to the broken line position as shown in Fig. 2. An operating stem 28 extends from one 50 end of the throttle 27 through a support 29 secured to and projecting from the valve body 6 which forms a support therefor. Attached to the outer end of the throttle stem 28 by means of a pin 30 is an operating arm 31 having a suit- 55

able connection for rotating the stem and the throttle 27 as desired. Between the arm 30 and the projection 29 and surrounding the stem is a coil spring 32 with their bearing washers 33 holding the throttle 27 yieldingly in any position in which it is set.

The outer end of the fuel passage 24 is closed in the block 6 by a plug screw 34 and extending transversely to the passage is another fuel passage 35 leading by means of a reduced portion 36 into the fuel chamber 10. In this passageway 34 an adjusting valve 37 is threaded having a pointed end 38 to adjustably close the reduced portion 36 and a head 39 extending without the body by means of which the valve is adjusted for admitting more or less fuel from the chamber 10 to the throttle chamber 8.

Communicating with one side of the fuel chamber 10 through a passage 40 at the bottom of the chamber is a vertical passage 41 in which a needle valve 42 is threaded having a pointed lower extremity 43 and an upper adjusting head 44. Extending laterally from the passage 41 above the pointed extremity of the needle valve 42 is a passage 45 formed in part by an angle fitting 46. Connected to the outer end of this fitting is a delay pipe 47, the other end of which is connected by an angle fitting 48 with the top of the fuel passage 7 but with a jet nozzle 50 extending into the passage from the top thereof and having jet openings 51 at the inner end.

Also mounted and rotatable in the fuel passage 7 is a choke valve 52 having an opening 53 in its lower edge and mounted for rotation upon a stem 54 which extends through opposite sides of the body member with a bearing nut 55 at one end and an operating arm 56 at the other end secured to a bearing sleeve 57 which is yieldingly held in place by a spring 58 and a nut 59 at the adjacent end of the stem 54.

The high speed nozzle 50 is positioned between the throttle valve chamber 8 and the choke valve 52 and in a partially closed position of the throttle 27 the high speed nozzle 50 will not be subject to sufficient suction to draw fuel therefrom. When the throttle is open to the fullest extent as shown in Fig. 2, and with the choke open the high speed nozzle 50 will be subject to considerable pressure, causing suction therein and an additional flow of fuel from this nozzle. The globules or particles of oil or fuel 60 as represented in Fig. 2, indicate the presence in the fuel passage of condensation or accumulation which is first taken up by the passage of high speed air through the carburetor when the throttle is opened.

Assuming that the gasoline engine to which the carburetor is applied is running at low or medium speed under partially open throttle, the low speed jet nozzle 25 only is in operation and supplying fuel. The full speed nozzle 50 is dormant; any fuel from this nozzle has returned to the fuel chamber 10 due to gravity. As the throttle 27 is opened for higher engine speeds the incoming fuel drawn by the increased suction from the engine acts upon the high speed nozzle 50 causing it to draw additional fuel from the float chamber 10 through the delay pipe 47. Due to the length or capacity of this delay pipe 47 a predetermined interval of time is necessary to fill the pipe before the fuel will be discharged from the high speed nozzle 50, thereby allowing time for the engine to receive most of the fuel which has accumulated throughout the various passages of the carburetor and the engine. This

will prevent too rich a fuel mixture from being supplied to the engine as soon as the throttle is opened wide and will cause a more normal and a more rapid acceleration of the engine from low throttle speeds to medium and full open throttle speeds. A continuation of the full open throttle will cause additional fuel to be drawn from the high speed jet nozzle thereby supplying sufficient fuel from the low and high speed jet nozzles for high speed operation of the engine.

It will be noted that the air inlet to the carburetor is first downwardly toward the low speed jet nozzle 25 and then inclines upwardly in the fuel passage 9, the throttle 27 causing in effect a restricted area at its low speed or partially closed position, the engine suction drawing the air directly over the nozzle 25 and its openings 26 to produce the desired suction.

When the throttle is closed or partially closed after being full open the engine suction is reduced on the upper jet nozzle and the fuel in the delay pipe 47 falls or returns by gravity to the fuel chamber 10.

Both of the jet nozzles are controlled by needle adjustments so that the amount of fuel can be varied as desired, and the throttle and choke valves are controlled in any well known manner by the movement of their operating members. Both the high and low speed jet nozzles receive fuel from the same fuel chamber and a single float is sufficient to maintain a proper level of fuel in the fuel chamber.

I claim:

1. A carburetor comprising a transverse air and fuel passage which first extends downwardly and then inclines upwardly through the carburetor body, a fuel feeding nozzle in the lowest part of the passage, a throttle valve for controlling the flow of air through the passage, a high speed fuel nozzle extending downwardly from the top of the passage at the rear side of the throttle, a common fuel chamber for the nozzles, and a delay pipe extending upwardly from the fuel chamber to the upper nozzle and having a predetermined capacity whereby the upper fuel nozzle delivers fuel to the passage only when the throttle is open a predetermined amount.

2. A carburetor having a transverse air and fuel passage, a throttle valve therein, a choke valve in the passage at a distance behind the throttle valve, a fuel feeding nozzle extending upwardly from the bottom of the passage adjacent the forward portion of the path of travel of the throttle valve, a second fuel nozzle extending downwardly from the top of the passage between the throttle and choke valves and in the path of air in the passage only when the throttle valve is opened to a predetermined extent, and a fuel feeding pipe for the second fuel nozzle which has a predetermined liquid capacity such that it is gradually filled with liquid depending upon the throttle opening which delays fuel feeding through the nozzle to that extent.

3. A delay feed carburetor comprising an air and fuel passage, a throttle valve therein, a fuel feeding nozzle in the bottom of the passage adjacent the forward portion of the throttle valve chamber, a high speed nozzle extending downwardly in the passage at the rear of the throttle, and a delay feed pipe extending from below the passage to the high speed nozzle and of a predetermined capacity such that the pipe must first be filled depending upon the setting of the throttle and the feeding of fuel therefrom is delayed

to a predetermined extent after the throttle valve is opened to its fullest extent in the fuel passage.

4. A delay feed carburetor having a transverse air and fuel passage, a throttle valve chamber and a valve movable therein, a low speed fuel nozzle extending in the bottom of the passage adjacent the front of the throttle chamber, the air and fuel passage back of the throttle valve 10 providing for the condensation and accumulation of surplus fuel therein, a high speed fuel nozzle extending downwardly at the top of the passage and being operative only when the throttle valve is opened to a predetermined extent, 15 a delay fuel feed pipe in connection with the high speed nozzle being effective only when the throttle valve is opened to a predetermined extent whereby the surplus fuel in the passage will first be taken up before the high speed nozzle is 20 effective after the opening of the throttle.

5. A delay feed carburetor having an air and fuel passage, a throttle valve therein, a high speed fuel nozzle in the bottom of the passage adjacent the valve, for low speed engine operation, a high speed fuel nozzle extending downwardly from the 5 top of the passage at the rear of the throttle valve, a common fuel chamber, a delay feed pipe extending from the chamber to the high speed fuel nozzle, the passage being adapted to receive the condensation and accumulation of the fuel 10 therein during low speed operation of an engine to which the carburetor is attached, and the high speed nozzle being effective only when the throttle is opened to a predetermined extent, the delay feed pipe preventing the discharge of fuel from 15 the high speed nozzle until a predetermined time after the opening of the throttle to take up the accumulation of fuel in the said passage before the high speed nozzle is effective.
